UNITED STATES PATENT OFFICE.

JOHN C. SUMMERS, OF MILLERSBURG, AND HARRY G. MAST, OF BENTON,
OHIO.

PUMP-STROKE REGULATOR.

No. 841,801.

Specification of Letters Patent.

Patented Jan. 15, 1907.

Application filed July 8, 1906. Serial No. 325,240.

To all whom it may concern:

Be it known that we, JOHN C. SUMMERS, residing at Millersburg, and HARRY G. MAST, residing at Benton, in the county of Holmes, and State of Ohio, citizens of the United States, have invented certain new and useful Improvements in Pump-Stroke Regulators; and we do hereby declare that the following is a full, clear, and exact description of the same, reference being had to the annexed drawings, making a part of this specification, and to the figures of reference marked thereon, in which—

Figure 1 is a perspective view showing our improved device mounted upon a platform and illustrating the same connected in operative relationship with the pump. Fig. 2 is a side elevation showing the arrangement of the worm-gear, the walking-lever, and pump connection. Fig. 3 is a section of the walking-lever, showing the same detached. Fig. 4 is a view showing the top or upper end of the toothed bar and its swivel connection to operating-rod. Fig. 5 is a section of the tube designed to hold and support the various parts connected to and carried thereby, also showing the transverse section of the toothed bar.

The present invention has relation to pump-stroke regulators; and it consists in the novel arrangement hereinafter described, and particularly pointed out in the claims.

Similar numerals of reference indicate corresponding parts in all the figures of the drawings.

In the accompanying drawings, 1 represents the platform, which may be located at any desired point with reference to the windmill, and upon this platform is mounted what we term a "jack," consisting of the power-wheel 2, the power-shaft 3, the gear-wheel 4, the pitman-gear wheel 5, and its shaft 6, said shafts 3 and 5 being mounted in suitable bearings 7. The jack and its different parts does not form within itself any particular part of the present invention, so far as its detailed construction is concerned, as the only object designed to be brought about is to impart a rocking or walking movement to the walking-lever 8 by means of the pitman 9 or its equivalent.

For the purpose of imparting motion to the pitman 9, and of course motion to the pitman

and to the walking beam or lever 8, the belt 10 is employed, which leads up to and is connected or located around the pulley driven by the windmill proper.

In the accompanying drawings no part of the windmill is illustrated, as it forms no particular part of the present invention so far as the windmill within itself is concerned, but a windmill of any construction may be employed, but must necessarily be located at a point where power can be transmitted to impart a walking movement to the walking-beam 8. To the platform 1 or its equivalent is secured the upright 11, to which upright is connected the tube 12, which is held by means of the clip 13 or its equivalent. It will be understood that the upright 11 should be of sufficient height to expose to the wind the vane 14 and the regulating-blade 15. The vane 14 is held in proper position by means of the bars 16, which bars are formed integral with or connected to the rings 17 and 18. The ring 18 rests upon the antifriction-rollers 19, which are carried by the flange 20. From the ring 17 extends the arm 21, to which arm is attached the bifurcated bar 22 by means of the brace-arm 23, said bar 22 being connected to the ring 18 by means of the short arm 24. However, we do not desire to be confined to this particular arrangement as to the bracing of the bifurcated arm 22, as the only object and purpose of said arm is to carry the bar 25, said bar being pivotally attached to the bifurcated arm 22, as illustrated in Fig. 1. The bar 25 is provided with the upright extended arms 26, to which is attached the regulating-blade 15, which blade is to stand normally in substantially a vertical position and is for the purpose hereinafter described.

To the platform 1 or its equivalent is connected the post 27, to the top or upper end of which is attached the housing 28, in which housing is located the toothed wheel 29, said toothed wheel 29 being mounted upon the shaft 30. The toothed wheel 29 is for the purpose of supporting and holding the walking-lever 8, said toothed wheel forming a fulcrum for said lever. The walking-lever 8 is provided with a series of teeth or toothed bars 31, which mesh with the teeth of the wheel 29, and when the wheel is rotated, as hereinafter described, the walking-lever 8

will be moved endwise by means of the teeth upon the wheel 29 and the teeth or bars 31. To the bar 25 is pivotally attached the regulating-rod 32, which regulating-rod extends downward and into the tube 12, and its bottom or lower end is connected to the rack-bar 33 by means of the yoke 34 and the flanges 35. The rack-bar 33 is extended downward and parallel with the upright 11 and held in proper position by means of the guides 36.

To the upright 11 is attached the housing 37, in which housing is journaled the shaft 38 and upon which shaft is mounted the pinion 39 and the gear-wheel 40. For the purpose of strengthening the housing 37 or producing a rigid structure and for the purpose hereinafter described the plate 41 is provided, which plate is attached to the housing 37 or to the upright 11, as desired.

It will be understood that when reciprocating movement is imparted to the rack-bar 33, as hereinafter described, rotary motion will be imparted to the pinion 39 and to the gear-wheel 40, which in turn imparts rotary motion to the pinion 42 and to the shaft 43, said shaft 43 being provided with the worm-gear 44, which worm-gear meshes with the gear 45, said gear being mounted upon the shaft 30, which is the shaft upon which the gear-wheel 29 is mounted, so that when rotary motion is imparted to the gear-wheel 45 rotary motion will be imparted to the gear-wheel 29, and of course reciprocating movement or endwise movement will be imparted to the walking-lever 8, the direction of movement of course being in relation to the direction of rotation of the gear-wheel 29.

For the purpose of holding the walking-lever 8 in proper mesh at all times the roller 46 is provided, which roller rests upon the top of the teeth 31.

For the purpose of regulating the pressure the screws 47 may be provided and are for the purpose of limiting the upward movement of the shaft 48, upon which the roller 46 is mounted. Another object in providing a means for adjusting the shaft 48 and its roller 46 is to take up the wear from time to time.

For the purpose of providing a counter-balance for the regulating-blade 15 the weight 49 is provided, which weight is so attached that it can be moved to or from the pivotal point of the arm 25. To one end of the walking-lever 8 is attached the pump-rod 50, which pump-rod is pivotally attached to the piston-rod 51 in the usual manner. The normal position of the regulating-blade 15 should be practically vertical, and when vertical the walking-lever 8 is fulcrumed about midway between the attaching-points of the pitman 9 and the pump-rod 50. When a strong wind is blowing, the blade 15 is moved at an angle to a vertical plane, and of course a strong wind imparts more power to the

windmill proper, thereby increasing the pumping facilities, and by moving the regulating-blade to a position out of a vertical one will lower the rack-bar 33, which in turn will move the walking-beam 8 endwise, as above described, and in the direction to bring the fulcrumed point of the walking-beam 8 nearer to the pitman end, thereby increasing the length of the stroke of the pump-rod 50, by which arrangement the increased power can be utilized.

The object and purpose of providing intermediate gear between the rack-bar and the pinion mounted upon the shaft 43 is to provide for a more extended longitudinal movement of the walking-lever 8, or, in other words, to give a more extended action to the walking-lever than would otherwise be given to it if the pinion upon the worm-shaft was located in mesh with the rack-bar, by which arrangement less movement is to be imparted to the regulating-blade 15. The plate 41, which is connected to the housing 37 or to the upright 11, is to provide a means for properly journaling the shaft 38 and the shaft 43. However, we do not desire to be confined to the particular arrangement described, as it will be understood various means may be employed for journaling the above-mentioned parts.

For the purpose of preventing any springing of the walking-lever 8 said lever may be provided with the short upright bars 52 and the truss-rod sections 53 provided, which are attached to the walking-lever 8 and are coupled together in the usual manner. In the drawings we have illustrated the jack located below the walking-lever, but it is simply a question of judgment, as in some instances the part which gives the walking-lever action may be located above the walking-beam, and the same object accomplished. The roller 46, which rests upon the top of the walking-lever, or, more specifically, upon the teeth of the walking-lever end mounted upon the shaft 48, must necessarily follow to a certain extent the movement of the walking-lever, and in order that this may be done we provide the pivoted plates or bars 54 and pivotally attach said bars to the housing 28.

For the purpose of returning the regulating-blade 15 to its normal position if it is forced by the wind into such a position that the weight 49 will be thrown or carried over its center or beyond a vertical line above the pivotal point of the bar 25 the spring 55 is provided, which spring is attached at one end to the lug 56 and the opposite end attached to the bar 25. For the purpose of stopping the bar 25 at a point so as to bring the regulator into its normal position the stop-flange 57 is provided, which stop-flange is extended from the bifurcated arm 22.

Having fully described our invention, what

we claim as new, and desire to secure by Letters Patent, is—

1. In a pump-stroke regulator, the combination of a pump-rod, a walking-lever, a fulcrum-wheel for said walking-lever, a pitman adapted to actuate the walking-lever, a pivoted lever provided with a weight, a regulating-blade, secured to said lever, a rod connected to the weighted arm of said lever, and a rack-bar actuated by the lever carrying the regulating-blade, an intermediate gear located between the rack-bar and the fulcrum-wheel and the walking-lever, substantially as and for the purpose specified. 5
2. In a pump-stroke-regulating device, the combination of a regulating-blade, a pivoted lever adapted to carry said blade, and provided with a weight, a rod pivotally connected to the weighted lever, a rack-bar actuated by the blade carried by the pivoted lever, a fulcrum-wheel and a walking-lever located thereon, and movable longitudinally, means for actuating the walking-lever and a pump-rod connected to said walking-lever, substantially as and for the purpose specified. 10
3. In a pump-stroke-regulating device, the combination of a toothed wheel, a walking-lever mounted upon said toothed wheel, pivoted arms located upon opposite sides of the walking-lever, a roller located upon said walking-lever and carried by said pivoted arms, means for imparting a walking movement to said walking-lever, and means for imparting rotary movement to the toothed wheel carrying the walking-lever, substantially as and for the purpose specified. 15
4. In a pump-stroke-regulating device, the combination of a walking-lever, means for imparting walking movement to the walking-lever, and means for imparting reciprocating movement to said walking-lever, a regulating-blade, and a pivoted lever adapted to carry said regulating-blade, a weight connected to said pivoted lever, a spring secured at its top end to the pivoted lever and its lower end secured in fixed relative position to the pivoted lever and a stop-shoulder adapted for contact with the under side of the pivoted lever, substantially as and for the purpose specified. 20
5. In a pump-stroke-regulating device a pivoted lever, a regulating-blade carried by said pivoted lever, a weight carried by the pivoted lever, rotatable members adapted to support said pivoted lever and regulating-blade and weight, a regulating-rod pivotally attached to the weighted lever, a rack-bar journaled at its top end to the regulating-rod, a pinion adapted to mesh with the rack-bar, a gear-wheel rotatable with the pinion meshing with the rack-bar, a shaft, a pinion fixed to said shaft, said pinion meshing with the gear driven by the rack-bar pinion, a worm-gear fixed to said shaft, a gear-wheel meshing with the worm-gear, a toothed wheel, a walking-lever fulcrumed upon the toothed wheel, said toothed wheel driven by the worm-gear and gear-wheel meshing therewith, and means for imparting walking movement to the walking-lever, and a pump-rod pivotally attached to said walking-lever, substantially as and for the purpose specified. 25

In testimony that we claim the above we have hereunto subscribed our names in the presence of two witnesses.
